UNITED STATES PATENT OFFICE.

JOHN E. DRAKE, OF QUINCY, MASSACHUSETTS.

EDGE-SETTING MACHINE.

SPECIFICATION forming part of Letters Patent No. 398,883, dated March 5, 1889.

Application filed June 23, 1888. Serial No. 278,061. (No model.)

To all whom it may concern:

Be it known that I, JOHN E. DRAKE, a citizen of the United States, and a resident of Quincy, in the county of Norfolk and State 5 of Massachusetts, have invented new and useful Improvements in Edge-Setting Machines, of which the following, taken in connection with the accompanying drawings, is a specification.

10 This invention relates to improvements on the patent issued to Patrick McLaughlin and myself December 6, 1887, No. 374,314, for edge-setting machines, and it is carried out as follows, reference being had to the accompanying 15 drawings, wherein—

Figure 1 represents a plan view of the invention, and Fig. 2 represents a cross-section on the line A B shown in Fig. 1. Fig. 3 represents a longitudinal section on the line C 20 D shown in Fig. 2.

Similar letters refer to similar parts wherever they occur on the different parts of the drawings.

a is the head or frame of the machine, provided with bearings a' a', in which is journaled the driving-shaft b, having at one end secured to it the pulley b', to which a rotary motion is imparted by means of belt-power, as usual.

30 The shaft b has between its bearings a crank or eccentric, b'', to which is pivoted the rear end of the connecting-rod c, the forward end of which is pivoted to the block d, that is guided between the longitudinally grooved or inclined ways or cap-plates a'' a'', secured in an adjustable manner to the frame or head a, or plates secured thereto, substantially as and for the purpose shown and described in the above-mentioned Letters Patent. In this manner a forward and back motion is imparted to the block d from the rotary driving-shaft b and its connections to said block. To the block d is secured in a suitable manner, or cast in one piece with it, the tool-carrier e, 35 that extends to one side of the head a and at or about a right angle to the same, as shown in Figs. 1 and 2.

f and g represent the edge-setting tools, one of which is intended for setting the sole-edge 40 around the toe and sides of the sole, and the

other one for the purpose of setting the edge at the shank portions of the sole.

f' and g' represent, respectively, upwardly-projecting shanks on said edge-setting tools, which shanks are guided and longitudinally 55 yielding in cylindrical perforations in the hubs e' e'', that form a part of the tool-carrying arm e, as shown.

The shanks f' g' are automatically forced downward with a yielding pressure against 60 the upward pressure on the shoe held by the operator by means of springs F G, the inner ends of which are suitably secured to the tool-carrier e, and having their outer free ends normally resting on the upper ends of the respective hubs e' and e'', as shown.

Projections e³ e³ on the lower ends of the perforated hubs e' e'' prevent the edge-setting tools from turning around during the operation of the machine.

70 For the purpose of preventing the shanks f' g' from dropping out of the perforated hubs e' e'', I make on said shanks the respective grooves or slots f'' g'', adapted to receive the spring-pressed pins f³ g³, that pass through 75 respective perforations in the hubs e' e'', and are attached to or form parts of the springs f⁴ g⁴, that are secured to the hubs e' e'', as shown in the drawings. By pulling said springs outward in their free ends the tool-shanks are released, and the tools may be removed for repairs or otherwise whenever so desired.

80 In a machine of this kind having the tool-carrier projecting to one side of the reciprocating block an unequal strain is caused on the reciprocating block and its guides, and to prevent this I extend the tool-carrier e in the form of an arm, E, projecting to the opposite side of the machine, as shown in Figs. 85 1 and 2, said arm terminating as a foot or rest, E', adapted to be supported on and slide on the stationary bar or guide a', that is secured to or cast in one piece with the frame 90 of the machine, as shown in Figs. 1 and 2. I prefer to cast the part E in one piece with the tool-carrier e; but, if so desired, said arm E may be secured to the carrier e or to the block d to equal advantage without departing 95 from the essence of my invention. By this 100

construction of the machine all unevenness of pressure on the block and its guides will be obviated, and consequently the device may be operated with more precision, with less amount 5 of frictional resistance, and to better effect as compared with others not provided with such extension and rest for it.

What I wish to secure by Letters Patent, and claim, is—

10 The edge-setting machine, as described, consisting of the stationary head or frame *a*, the reciprocating block *d*, mounted therein, and the tool-carrier *e*, secured to or forming a part of said block and projecting to one side of

said head or frame, combined with the stationary guide *a'*, and the arm or extension *E*, forming a part of or secured to the tool-carrier *e* or the block *d*, and suitable tools arranged on the said carrier *e*, substantially as and for the purpose set forth. 15

In testimony whereof I have signed my name to this specification, in the presence of two subscribing witnesses, on this 9th day of June, 20 A. D. 1888.

JOHN E. DRAKE.
